UNITED STATES PATENT OFFICE.

ARTHUR V. DA COSTA, OF ARLINGTON, NEW JERSEY, ASSIGNOR TO THE INSEL COMPANY, OF NEWARK, NEW JERSEY, A CORPORATION OF NEW JERSEY.

TOY.

1,299,430.

Specification of Letters Patent.

Patented Apr. 8, 1919.

Application filed May 13, 1918. Serial No. 234,120.

To all whom it may concern:

Be it known that I, ARTHUR V. DA COSTA, a citizen of the United States, and a resident of Arlington, in the county of Hudson and State of New Jersey, have invented certain new and useful Improvements in Toys, of which the following is a specification, reference being made to the accompanying drawings, forming a part thereof.

10 The invention relates to toys and a main object of the invention is to construct a toy that is made entirely, or substantially entirely, of celluloid.

15 The invention particularly relates to a rattle which is used by small children and an object of the invention is to provide a construction that will withstand rough usage, that will be light and will not injure small children even though it is used by them in 20 a rough manner, and furthermore to so construct the toy in such a manner that it will not damage furniture even though the toy is hammered and banged by the child against the furniture.

25 Another object of the invention is to construct the toy in such a manner that it will fascinate the child or hold its attention due to the peculiar characteristics and movements of the members which together make up the rattle.

30 This desired effect is enabled to be realized by securing a hollow bulbous member containing a loose member or loose members to the free end of a spring or flexible spiral member whereby a series of quick springy movements can be imparted to the bulb at the free end of the spring. The spring as well as the bulbous member just referred to is preferably made of celluloid although 35 it will be understood that according to the broader aspect of the invention the spiral and bulbous member may be made of other

40 materials. According to a more intense aspect of the invention, however, the spring is of celluloid, the bulb is of celluloid, and in fact all portions of the toy are of celluloid with the possible exception of the pieces or members that may be located within the bulbous member or members, if there are 45 more than one, for the purpose of producing the desired noise effects.

50 The invention is directed to the features of construction above referred to as well as

to other features, all of which features are hereinafter fully described and clearly set forth.

As illustrating certain specific embodiments of the invention, reference is made to the accompanying drawings forming a part of this specification, in which drawings—

Figure 1 is a view, partially broken away, showing a toy or rattle having bulbous members at each end thereof of celluloid which are connected by a spiral spring member made of celluloid. In each of the hollow bulbous members there is located a number of small pieces or members for producing the desired noise effects.

Fig. 2 is a sectional view taken as on the plane indicated by the line 2, 2 in Fig. 1.

Fig. 3 is a view of a toy, partially broken away. In the toy shown in Fig. 3 there is a handle member in the form of a hollow ring, a hollow bulbous member, and a spring connecting the handle member and the hollow bulbous member. This toy is also constructed so that it can be made substantially entirely of celluloid.

Fig. 4 is a toy, in the form of a manikin, comprising a body portion to which members resembling a head, hands and feet are connected by celluloid spirals.

Fig. 5 is a view, partially broken away, of another form of toy. In Fig. 5 there is shown a hollow member in the form of a bell-shaped member containing therein a noise producing member such as a small brass bell. In this figure there is also shown a hollow bulbous member serving as a hand-engaging member or handle, and a spiral spring connecting the hollow bulbous member and the hollow bell-shaped member.

The several toys will now be described in detail.

The toy shown in Fig. 1 has the large hollow bulbous member 1—which is in effect a modified sphere approaching a hollow ellipsoid—a small hollow spherical bulbous member 2, and the spiral member 3 of celluloid. The bulbous members are made of two parts. The bulbous member 1 comprises the parts 4 and 5 which have an overlapping joint at 6 and the parts are cemented together by suitable celluloid cementing material. The two parts of the bulb 2 are designated by 7.

and 8 and have a joint at 9, as is clearly shown in Fig. 2. The hollow bulbous members made in the manner just described provide a strong construction and one which withstands the rough usage to which toys of this class are subjected, as by the child hammering or banging the toys against solid or hard objects. The spiral member 3 may be referred to as a spiral spring member 5 of celluloid and the opposite ends of the spiral are firmly cemented to the bulbs. The bulb 2 may be referred to as the hand-engaging member, while the bulb 1 may be referred to as a swinging bulb located at one 10 end of the spiral spring member 3, or reversely the bulb 1 might be considered as the hand-engaging member or handle, while the bulb 2 might be looked at as a swinging bulb. Noise producing means 10 and 11 15 are provided in each of the bulbs 1 and 2 respectively. The noise producing means shown in this figure is made up of a number of small members or hard pieces that rattle or shake about within the hollow bulbous 20 members to produce the desired noise effects for attracting and holding the attention of the child. These noise producing means 10 and 11 may be in the form of small metallic objects, but with this exception all of the 25 rest of the toy is preferably of celluloid.

The toy shown in Fig. 3 is similar in its construction to the toy shown in Fig. 1 with the exception that in Fig. 3 a hollow ring 12 is provided as the hand-engaging member 30 or handle and this hollow ring is secured to one end of the celluloid spiral 13 by the connection 14 comprising the loop 15 and the hollow spacer 16, the latter of which is cemented to the lower end of the spiral 13. The bulbous member 1^a at the upper end of the toy is hollow and contains suitable noise 40 producing means.

The manikin shown in Fig. 4 comprises a hollow bulbous body member 17, a hollow bulbous head member 18, miniature hands 19 and feet 20, and the springs 21, 22 and 23 which respectively connect the head, hands and feet to the body portion 17. The parts constituting the manikin are of course properly secured to each other, as by cement, and all the several parts that are secured to the body portion have a substantial movement relative to the body portion due to the springs or spiral connections described. Suitable noise producing means can be inserted within the bulbous body portion 17, the bulbous head portion 18 or even in the hand portions 19 or the foot portions 20.

In Fig. 5 there is shown a toy in the form 60 of a bell and rattle, and this toy comprises a hollow hand-engaging bulb 24, a bell-shaped member 25, and a spiral 26 that connects the hand bulb 24 to the bell portion 25. The bell portion 25 has a diaphragm or 65 closing plate 27 at the lower portion thereof

so as to retain in the bell-shaped member 25 a small brass bell as 28, which serves as a noise producing member within the hollow bell portion 25. Should the child hold the bell-shaped portion 25 in its hand then the portion 25 would become a rattle since the noise producing means is contained in the hollow bulbous portion 24. With the possible exception of the noise producing means which is employed within the several hollow bulbous portions, all of the toys so described are made of celluloid as previously indicated. The spiral members connecting the several parts may be referred to as spiral celluloid springs that permit a rapid swinging or vibrating of the bulbs located at the free end of the spring when slight changes of force are applied at the hand-engaging portion of the toy for the purpose of effecting this movement. It will be manifest, however, that the invention in its broadest aspect is not limited to the employment of celluloid as the principal material although in the more specific aspect of the invention celluloid is the material that is used. The spiral member herein described may be referred to as, and in fact is, a flexible member made from a rod wound in the form of a spiral. It is also manifest that the invention can be embodied in various forms and modifications without departing from the spirit and scope thereof.

What I claim is:

1. A child's toy, in the form of a rattle, comprising in combination a spiral spring 100 of celluloid material, a handle connected to said spring at one end thereof and a hollow bulbous member containing a loose member or loose members, which bulbous member is connected to the spring at the other end 105 thereof.

2. A child's toy, comprising in combination a hand member, a swinging bulbous rattle member containing a movable member or movable members, and a spiral spring member 110 connecting the hand member and the swinging bulbous rattle member.

3. A child's toy, comprising in combination a hollow bulbous member of celluloid containing loose pieces or members, a hand member of celluloid, and a flexible celluloid member formed of a celluloid rod wound in the form of a spiral and having one end of the spiral connected to the hand member and the other end of the spiral connected to the bulbous member.

4. A child's toy, comprising spaced hollow bulbous members, each of celluloid, that are connected to each other by a celluloid spiral, one end of which spiral is connected 125 to one of the bulbous members and the other end thereof is connected to the other of the bulbous members.

5. A toy, comprising in combination a hollow bulbous member containing therein noise.

producing means and a celluloid spiral to which the bulbous member is secured.

This specification signed and witnessed this 11th day of May, A. D. 1918.

6. A child's toy, comprising in combination a hollow member containing a noise producing member and a spiral member to one end of which spiral member the hollow member is secured.

ARTHUR V. DA COSTA.
